UNITED STATES PATENT OFFICE.

JOHN U. TOLLES, OF VIRGINIA CITY, NEVADA.

IMPROVEMENT IN CONCENTRATING-TABLES FOR ORES.

Specification forming part of Letters Patent No. 177,174, dated May 9, 1876; application filed January 22, 1876.

To all whom it may concern:

Be it known that I, J. U. TOLLES, of Virginia City, in the county of Storey and State of Nevada, have invented certain Improvements in Concentrators, of which the following is a specification:

My invention consists in the combination of a stationary flat inclined table, having a cloth-covered surface, with a stationary feeding-box at its upper end; in a peculiar construction of the feed-box; in a receiving-box and a hinged leaf arranged at the lower edge of the table; and in a rotating perforated pipe located above the table to deliver a sheet of water thereon, for the purpose of driving the collected particles into the receiving-box, as hereinafter described.

Figure 1 represents a perspective view of my machine; Fig. 2, a top plan view of the same; Fig. 3, a vertical cross-section of the same.

A represents a flat inclined table, provided with a surfacing, *a*, of cloth of any suitable kind, and with ledges *b*, to prevent the material from passing over the ends. B represents a feed-box extending along the upper edge of the table, and provided in its front side with a row of discharge-openings, *c*, of the form shown, each narrowing down to a point at its lower end. C represents a receiving trough or box extending along below the lower edge of the table. D represents a leaf or board hinged to the rear side of the trough or box C, in such manner that it may be turned under the edge of the table, to conduct the material therefrom into the box, as shown in Fig. 2, or turned back, as shown in Fig. 1 and in dotted lines in Fig. 2, so that the material passing over the edge of the table will be discharged outside of the box. E represents a rotating tube suspended lengthwise above the upper edge of the table by endless belts *d* passing over pulleys *e*, supported in the rigid frame F. The tube is provided from end to end with a row of perforations, *g*, and with a hand-lever, *h*, at one end, and is connected by a pipe, *i*, with a reservoir or pump delivering water at a pressure corresponding to a head of from eight or twelve feet.

In operating the machine the feed-box B is partly filled with rough stones to insure an

even distribution and a steady flow of the material to be treated, a steady and copious supply of water maintained in the box, and the ore, sand, or tailings introduced therein. The water escaping through the openings *c* flows down in a thin film or stream over the face of the table holding the material in suspension. The heavy and valuable particles are deposited upon and retained by the cloth surface of the table, while the light refuse particles are carried over the lower edge and discharged outside of the box C.

After the collection of a suitable amount of metal upon the table, the supply of water to the feed-box is stopped, the leaf D turned under the edge of the table and water supplied to the pipe or tube E, by which it is delivered through the perforations upon the table in a row of fine jets forming an almost continuous sheet or film.

By means of the lever *h* the pipe or tube E is rotated, and the sheet of water swept over the table from top to bottom, so as to drive all adhering particles therefrom and wash them down into the collecting-box C. After this operation the jets are stopped, the leaf, turned out, and the feed-water again started. By employing the cloth surface, giving the table the proper inclination, and properly regulating the flow of water, I find that I can effect a rapid and thorough separation without agitating the table, and without the employment of manual labor for any other purpose than that of feeding the material; and by the employment of the fixed table with its cloth surface I can separate particles which cannot be retained in machines which vibrate. By the use of the feed-openings *c* of the form shown, I render the discharge of the sand ore or other fine material very steady and gradual, as it will be carried through the narrow portion of the openings while the lighter water will pass over the same, through the upper large end of the openings, taking up the material gradually and distributing it evenly upon the table. It is obvious that the rotating tube may be sustained in any other suitable manner, and that it may be connected in any suitable manner with the source of water-supply.

The object in arranging the perforated pipe

so that it can rotate is to permit a gradual change in the direction of the jets, so that their point of impact upon the table can be advanced from its upper to its lower edge, and thereby every portion of the surface subjected in turn to the direct impact of the jets, in order to effectually loosen and drive forward the particles therefrom.

Having described my invention, what I claim is—

1. In a concentrator, the combination of a stationary inclined flat table, A, provided with a cloth facing and a stationary feed-box, provided with perforations, and arranged to deliver the ore and water upon the table, as shown and described.

2. The feed-box B, provided with the discharge-openings c, of decreasing width toward their lower ends, as shown.

3. In combination with the inclined concentrator-table A, the collecting-box C and hinged leaf D, as and for the purpose described.

4. In combination with the concentrator-table A, the rotating perforated tube E, substantially as and for the purpose described.

5. The feed-box B, provided with the openings c, and partially filled with the rough stones, as and for the purpose described.

6. The combination of the inclined cloth-covered table A, the feed-box B, and the rotating perforated pipe E.

JOHN U. TOLLES.
